UNITED STATES PATENT OFFICE.

WILLIAM L. TAYLOR, OF CINCINNATI, OHIO.

MULTIPLEX BAG AND THE METHOD OF MAKING IT.

Application filed November 21, 1925. Serial No. 70,592.

My invention relates to paper bags and more particularly to such bags having more than one ply of paper for use as tobacco containers.

5 The objects of my invention are to simplify and cheapen the method and means of construction of the bag; to insure accurate and proper registration of the plies of paper during the operation of making them; 10 to provide greater pliability of the finished bag whereby heavier plies of material may be used without undesirable stiffness in the sides of the bag when shaping it for receiving the contents and also when making the 15 closure at the top after the contents are filled in.

Other objects and advantages are obtained as herein set forth.

My invention consists in taking two long 20 strips of paper of different widths and gluing them together at intervals a short distance away from their longitudinal edges whereby said plies are held in absolute registry with each other during all subsequent 25 operations, then dieing out the individual bag blanks from said longitudinal strips whereby the narrow side of each ply will be of the same dimension and whereby the longitudinal edges of said narrow side will 30 be glued together.

My invention also consists in the various steps required to form the completed bag, and in the bag as an article of manufacture.

In the drawings:

35 Fig. 1 is a view of the outer ply or cover of a bag blank;

Fig. 2 is a view of the inner ply or liner of the bag blank;

40 Fig. 3 is a view of the inner and outer plies of the bag blank glued together along the longitudinal edges of the narrow side;

Fig. 4 is an isometric view of the bag blank shown in Fig. 3 after the longitudinal flaps of the wider side have been folded inwardly and coated with glue on their exposed surfaces with the narrower side partly folded into position;

Fig. 5 is a top view of the open end of the bag showing the sides glued together 50 along their longitudinal edges;

Fig. 6 is an isometric view of the completed bag;

Fig. 7 is a transverse section on the line 7-7 of Fig. 4;

55 Fig. 8 is a transverse section on the line 8-8 of Fig. 4;

Fig. 9 represents two long superposed strips of paper of different widths pasted together at intervals a short distance from 60 their longitudinal edges;

Fig. 10 is a similar view showing by dot and dash lines the parts cut away in forming the individual bag blanks; and

Fig. 11 is a view similar to Fig. 10, showing one of the bag blanks detached and the 65 discarded or waste parts cut away.

The preferred method of making bags in accordance with my invention consists in taking long strips of paper 1 and 2 in rolls of different widths and by suitable means securing them together at intervals a short distance from their longitudinal edges by narrow bands of glue 3, as shown in Fig. 9, so that when the individual bag blanks are die 70 out from this multiply strip of paper, the plies of the narrow side of the bag blank along its longitudinal edges will be securely held in registry by the bands of glue and the outer or cover ply of the wider side will be narrower than the inner ply or liner, as 75 shown in Figs. 3 and 11.

The cover or outer ply 4 is formed of narrow side 5 and wider side 6 with securing flaps 7 along its longitudinal edges, as shown 80 in Fig. 1.

The liner or inner ply 8 comprises narrow side 9 and wider side 10 having securing flaps 11 along its longitudinal edges and adapted to be folded inwardly to the width of the narrow side, as indicated by the dotted lines. The liner, as shown in Fig. 2, is of the same shape as the cover shown in Fig. 1, except that the flaps 11 of the liner are wider than the flaps 7 of the cover.

As previously stated, the long strips of 90 paper are secured together at intervals by bands of glue or other adhesive material, as shown in Fig. 9, so that when each bag blank is die cut from said band it will comprise the two ply blank, as illustrated in 100 Figs. 3 and 11, in which the glue band 3' extends along each longitudinal edge of the narrow side only of the bag.

The bands of adhesive material 3 which bind the strips of paper together at intervals are preferably formed sufficiently wide so that when the bag blanks are die cut the die cuts through and removes a small part of the adhesive material in order to insure complete adhesion of the plies along 105 their longitudinal edges, as clearly shown at X in Figs. 10 and 11.

The next step consists in folding the flaps 7 and 11 inwardly, as shown in Fig. 8, then applying glue 12 thereto, as shown in Fig. 4, and then folding the narrow side of the 5 bag blank thereon to form the completed bag, as shown in Figs. 5 and 6.

An important advantage of my invention consists in securing registration of the respective plies of material from side to side 10 by gluing them together in such relationship at intervals before dieing out the individual bag blanks, as shown in Fig. 11. This insures proper registration of the superposed strips or webs during all subsequent operations, including the gluing of the securing 15 flaps and folding and gluing the bag sides together. It also insures registration of the strips of paper when being folded in a single set of formers. It has the advantage of requiring only one set of dieing out and cutting 20 cylinders and one waste exhaust system to receive the waste material cut away. It permits the use of simplified mechanism, making more speedy and efficient adjustment of the machine; has the advantage of 25 a greater quantity of paper in dieing out moisture-proof and insulated papers, such as are combined with asphalt, that is to say, the greater the thickness of the paper in relation to the quantity of asphalt, the greater 30 cleaning effect it will have upon the knives of the dieing-out mechanism. As too limited a quantity of asphalt does not give moisture-proof quality it is highly desirable 35 to fabricate materials for use in bags in such a manner as will allow a maximum quantity of asphalt with efficient operation.

Gluing the narrow sides of the blanks together, along their longitudinal edges will 40 not allow displacement of the liner in subsequent packing operations. Gluing the blanks together only on the narrow side and not gluing the inturned flaps together but merely gluing the narrow side of the blank 45 to the inturned flaps allows the liner to float freer into position when the bag is being packed with material such as tobacco, and gives greater pliability to the bag by being so glued, so that it is possible to use heavier 50 plies of paper or other material and not have undesirable stiffness in the side of the bag when shaping it for receiving the contents and also when making the closure at the top, after the contents are filled in. Blanks 55 glued together in this manner can be gripped more positively in the delivery

mechanism of the bag machine, especially when a paraffin liner is used as one ply thereof, the coating of paraffin having a tendency to compress under the gripper bar 60 and making it more difficult to hold and deliver. The liner being glued into position will insure greater accuracy in the final fold when pressure must be exerted on the point where the bag is glued together. This will 65 avoid, in a large measure, an undesirable bias fold if the pressure on the delivery mechanism is not accurate or uniform.

While I have set forth a particular construction and method of making the bags, it 70 will be understood that it is capable of modification without departure from the scope or spirit of the invention, as defined in the claims, as for instance, a larger number of plies than two may be employed, if desired. 75

What I claim as new and desire to secure by Letters Patent is:

1. The herein described method of forming a multiplex bag which consists in taking strips of paper of different widths and securing them together with bands of adhesive material at intervals in spaced apart relation from their edges, then dieing out the individual bag blanks from said multiplex strip, cutting through the adhesive material and discarding part thereof and forming one side of the bag narrower than the other side thereof, then folding the edges of each ply of the wider side inwardly to form 90 securing flaps, then coating the exposed surface of said securing flaps with adhesive material and then compressing the narrower side against said adhesive material whereby the completed bag is formed. 95

2. The herein described method of forming a multiplex bag which consists in gluing together superposed strips of paper of different widths at spaced apart intervals near their longitudinal edges to form a multiplex strip, then dieing out from said multiplex strip individual bag blanks each having one side wider than the other side and one side of the lining wider than the adjacent cover whereby securing flaps are provided, then folding said securing flaps inwardly, then gluing the exposed surface thereof, then folding said blank transversely and pressing the sides of the bag together upon the glued flaps to form the completed bag. 100 105

WILLIAM L. TAYLOR.
